UNITED STATES PATENT OFFICE.

JOHN D. ALLEN AND HARRY B. WALMSLEY, OF LYNN, MASSACHUSETTS.

TRIMMING MECHANISM FOR SEWING-MACHINES.

SPECIFICATION forming part of Letters Patent No. 248,977, dated November 1, 1881.

Application filed December 13, 1880. (No model.)

To all whom it may concern:

Be it known that we, JOHN D. ALLEN and HARRY B. WALMSLEY, both of Lynn, in the county of Essex and State of Massachusetts, have invented certain new and useful Improvements in Trimming Mechanisms for Sewing-Machines, of which the following is a full, clear, and exact description.

This invention relates to an improved mechanism to be combined with and arranged upon any of the ordinary sewing-machines, and to be operated in conjunction therewith for trimming or cutting from time to time the material being sewed, and in a line parallel with the line of seam or stitch, and it is especially useful and applicable in leather sewing for boots and shoes and other articles of leather manufacture.

This improved mechanism in itself and in its connection with sewing mechanism consists, in substance, of a bar which carries a cutting blade or knife suitable to cut and trim, as desired, the material being sewed, and which is located and arranged at one side of the needle-bar to move and be guided vertically and in a parallel line therewith, and to have its knife-edge at or near, but preferably at and in advance of, the sewing-needle, in combination with two springs, which are arranged upon or in relation to said knife-bar (the one above the other) for each to be downwardly compressed in a downward movement of the needle-bar, and to be relieved of such compression in an upward movement of the needle-bar and otherwise, all in such manner that through the downward compression of the one spring the cutter-bar is moved downwardly, carrying with it its knife-blade into and through the thickness of the material being sewed, and the other

spring is compressed downwardly, and that through the upward release of the downward pressure upon the spring, the downward compression of which moved the cutter-bar downwardly, the other spring is released to react in an upward direction upon the cutter-bar, and thus to raise the cutter-bar to its normal position, to be again acted upon, as above, in the next downward movement of the needle-bar.

In the accompanying plate of drawings the present invention is illustrated in connection

with a Wheeler & Wilson sewing-machine, Figure 1 being a side elevation of the needle end of the machine and above the bed-plate; Fig. 2, a vertical section on line *xx*, Fig. 1, 55 and looking toward the needle end of the machine; Figs. 3 and 4, horizontal sections on line *yy* and *zz*; Fig. 5, a sectional view in detail.

In the drawings, *a* represents the needle, 60 and *b* the needle-bar, of the sewing-machine, arranged and working as usual.

c is a bar having fixed to one end of it a knife or cutting blade, *d*. This bar *c* is at one side of the needle-bar, and is there arranged to move and be guided and play vertically and in a parallel line with the needle-bar, and to have the cutting-edge *f* of its blade presented downwardly to the throat-plate back of the needle and in a line commencing at or 70 near the needle and extending in advance thereof, or, in other words, in the same direction as that of the travel of the material being sewed by the feed of the machine.

g *h* are two spiral springs surrounding the 75 knife-bar *c*, and arranged the one above and separately from the other. The upper spring, *g*, at its lower end rests upon a fixed collar, *l*, (but adjustable vertically by set-screws *m*) of the knife-bar *c*, and the lower spring, *h*, at its 80 lower end rests upon a stationary bearing, *n*, of the head-stock *A* of the machine, through which both the needle and knife bars *b* *c* move. Above the upper end of the upper spring, *g*, the knife-bar *c* is surrounded loosely by a horizontal arm, *o*, fixed to the needle-bar, but adjustable vertically by set-screw *p*, and above the upper end of the lower spring, *h*, the knife-bar is provided with a collar, *r*, fixed to it, but adjustable vertically by set-screw *s*. 85

The upper spring, *g*, and its under supporting-collar, *l*, of the knife-bar, together with the horizontal arm lapping from the needle-bar over the upper end of such spring, are adjustable in such relation to each other that in the 95 downward movement of the needle-bar its needle will have first entered into the material being sewed before the said horizontal arm *o* will abut against the upper end of the upper spring, *g*, and that in the then continued downward movement of the needle-bar to the completion of its stroke in that direction the said 100

arm will bear downwardly upon the said spring, and by compressing it against the collar of the knife-bar, which supports it at its lower end, force the said knife-bar in a downward direction, and thus cause the cutting-edge of the knife, which is carried by it, to enter into and through and cut the material being sewed, the portion of such knife-edge being first suitably adjusted therefor.

10 The lower spring, *h*, and collar *r* of the knife-bar at its upper end are adjusted in such relation that the downward movement of the knife-bar through the downward movement of the needle-bar, as above described, will downwardly compress such spring *h* against its stationary support without at the same time, to any material or practical extent, interfering with the downward movement of the knife-bar by the compression of its upper spring, as aforesaid. The needle-bar, having completed its downward stroke, then moves upward, and as it so moves it releases the downward pressure or compression on the upper spring through its horizontal arm *o*, and thus the lower spring, 25 *h*, is left free to react upwardly against the collar *r* of the knife-bar, which is at its upper end, of such spring, through which reaction, as the needle-bar continues and before it finishes its upward stroke, the knife-bar is finally raised 30 to its normal position to be operated upon as before in the next and succeeding downward movement of the needle-bar. In this manner it is plain that the cutting-edge of the knife is made from time to time to cut into and through 35 the material being sewed, and obviously, if its cutting-edge be properly situated relative to the needle, and the material be properly guided through the machine, a trimming of the material being sewed will and can be had in a line 40 parallel with the line of sewing or seam.

The knife-bar *c* may be round or square-sided, and in either case the guideways *n* *t* for it are to be correspondingly shaped, and obviously when square-sided no rotary movement of it can occur as it travels up and down; but when round, while such might be the case, yet it is easily prevented, and in many obvious ways—as, for instance, such as shown in the drawings, which consists in providing its upper collar, *l*, with a vertical pin, *u*, to play into and through a hole, *v*, in the head-stock of the machine.

The trimming mechanism herein described obviously may be operated directly from the 55 arm which throws the needle-bar, instead of

from the needle-bar, as has been described, and again directly from the driving parts of the machine, instead of through either the needle-bar or the lever-arm operating it, the essential part in this regard being to simply secure downward pressure upon the knife-bar under a principle of operation substantially such as has been described. Again, the downward pressure desired upon the knife-bar may be put upon it as well through the lower spring as the upper spring, provided, of course, the relative arrangement of the spring be reversed. The point of the knife-blade is of such length that it is never lifted above and out from the guiding-slot in the usual throat near the needle-hole.

Having thus described our invention, what we claim, and desire to secure by Letters Patent, is—

1. In a sewing-machine, a knife-carrying bar 75 adapted to be moved vertically in guideways, in combination with two springs, one of which is arranged in relation to said bar and to the operating mechanism of the machine to secure a downward movement of the knife-bar under 80 a compression of the spring, and the other an upward movement thereof on a release of such compression, whereby the knife-bar is raised to and held in its normal position, ready for operation again, substantially as and for the 85 purpose described.

2. In a sewing-machine, a knife-carrying bar adapted to be moved vertically in guideways, and having collars or shoulders *l* *r* and springs *g* *h*, in combination with an arm, *o*, raised and 90 lowered by the operating mechanism of the machine, to secure the lowering and raising of knife-bar *c*, all substantially as and for the purpose described.

3. In a sewing-machine, a knife-carrying bar 95 adapted to be moved vertically in guideways, and having collars or shoulders *l* *r* and springs *g* *h*, in combination with the arm *o* of the needle-bar *b*, all severally arranged for a co-operative action in the downward-and-upward 100 movement of the needle-bar, substantially as and for the purpose described.

In testimony whereof we have hereunto set our hands in the presence of two subscribing witnesses.

JOHN D. ALLEN.
HARRY B. WALMSLEY.
